VENDING MACHINE CABINET FOR CARDS, OR FLAT PACKAGES OF MERCHANDISE

Irving Pitel, North Babylon, N.Y., assignor to Calex
Manufacturing Inc., Amityville, N.Y., a corporation of New York

Filed Apr. 20, 1959, Ser. No. 55,577

Term of patent 14 years

(Cl. D52—3)

Figure 1 is a perspective view of a vending machine cabinet for cards, or flat packages of merchandise, showing my new design;

The undisclosed side is the same in appearance as the side shown, and the rear is plain.

I claim:

The ornamental design for a vending machine cabinet for cards, or flat packages of merchandise, substantially as shown and described.
